UNITED STATES PATENT OFFICE.

JOSEPH W. SHARP, JR., OF PHILADELPHIA, PENNSYLVANIA; ASSIGNOR TO HAINES, JONES AND CADBURY COMPANY, OF PHILADELPHIA, PENNSYLVANIA, A CORPORATION OF PENNSYLVANIA.

COCK OR FAUCET.

No. 893,944.

Specification of Letters Patent. Patented July 21, 1908.

Application filed December 7, 1906. Serial No. 346,780.

To all whom it may concern:

Be it known that I, JOSEPH W. SHARP, Jr., a citizen of the United States, residing at Philadelphia, in the county of Philadelphia and State of Pennsylvania, have invented new and useful Improvements in Cocks or Faucets, of which the following is a specification.

The present invention relates to cocks or faucets, and has for its object to provide a cock which is peculiarly adapted for laundry tubs, although useful in connection with toilet bath tubs. Its value in connection with baths resides in the fact that its construction is such as to prevent the filling of pails or rinsing of receptacles beneath it; while in laundry tubs it is particularly useful for the reason that there are no projecting and depending nozzles to catch and tear delicate fabrics which are being laundered. Furthermore, the cock is so constructed that it will deliver water at full capacity with a minimum volume of noise; and its structural design renders it convenient to make and easy to secure to the pipe connection of the tub or stand.

Briefly stated the invention resides in a cock or faucet designed to be located within a tub or vessel and having its outlet arranged to discharge along a substantially vertical wall thereof, comprising a valve-chamber provided with means whereby it may be secured against the vessel wall, a discharge passage opening radially through a wall of the chamber, means for determining and positioning the said discharge passage close to the vessel wall to secure the stated objects, a valve and valve-seat arranged in said chamber, and exposed means for manipulating the valve to control the flow of fluid through the discharge passage.

The invention resides further in a faucet of compact form wherein the casting in which the valve-chamber is formed is provided at its base with an abutment, which may be in the form of a scutcheon, face-plate or flange adapted to abut the wall to which the faucet is to be attached, and a radial discharge passage leading from the valve chamber and traversing said scutcheon, face-plate or flange, as distinguished from those prior constructions wherein the discharge passage is in the form of a spout projecting from the valve-chamber at a point removed from the base of the casting.

In the drawings herewith I have illustrated one embodiment of my invention in order that the same may be clear to those skilled in the art, and in said drawings—Figure 1 is a central vertical section of a cock constructed in accordance with my invention, a section of the tub wall being shown, together with the pipe connection; Fig. 2 is a view in front elevation of the cock, the valve being removed; Fig. 3 is a view looking at the delivery opening.

Referring to the drawings by numerals, like numbers indicating like parts in the several views, 2 indicates the tub wall, perforated for the passage of the nipple of the cock 70 to engage the coupling 3, which connects the pipe 4 and the cock, a washer 5 being provided against which coupling 3 bears when it is set up to draw the cock snugly to position, all as shown in Fig. 1.

The cock proper embodying means for determining and positioning the delivery passage, presently to be described, close up to or against the wall of the vessel 2, to secure the stated objects. This means in the arrangement illustrated comprises a face plate or scutcheon 6 of any desired form, it being shown round in its present embodiment, the said plate 6 being comparatively thin so as to substantially merge into and break but slightly the surface of the wall 2 against which it rests.

Projecting rearwardly and centrally of the plate 6 is the threaded setting-up nipple 7, which, as above stated, forms the means of securing the cock and inlet pipe together through the medium of the coupling. Projecting forwardly and centrally of the plate 6 is the valve casing 8, the interior of which is enlarged to form a chamber 9, which may be 90 internally threaded to receive the threaded valve 10, said valve 10 having a fiber washer 11 at its seating end which bears against a seat 12 formed on a slightly contracted ring 13 intermediate the valve casing 8 and nipple 100 7; and an operating stem 14 and handle 15 projecting from its other end; a packed cap 16 closing the end of the valve chamber 9, as clearly shown in Fig. 1.

The plate 6 has a radial enlargement or thickened section 17, which is channeled with a straight-way delivery passage 18 leading to the chamber 9 of the valve casing and discharging therefrom at substantially right angles to the inlet leading to the valve cham- 110

ber, said delivery passage being preferably of the flattened form shown in Fig. 3, so as that great capacity of flow without undue enlargement of the plate at this point is secured.

It will be seen that the construction is such that a straight through passage is formed centrally of the cock; which through passage is intersected at right angles by the straight 10 delivery passage, and this admits of ready casting of the cock in the rough and the easy machining of the valve seat and traversing threads in the bore of the valve chamber. Furthermore, the cock is formed in a single 15 piece with a minimum amount of metal and the necessity of independent scutcheons and finished washers is entirely done away with.

Reference to Fig. 1 shows that the disposition of the delivery passage 18 relative to 20 the wall 2 of the tub is such that the discharge from the cock will be in the form of a thin broad stream from the flattened delivery opening, which will flow down the face of the tub wall noiselessly, and formation of jets 25 will be entirely avoided. This same disposition of the delivery opening in such close proximity to the wall of the tub as to prevent the formation of jets, prohibits the filling of pails or the rinsing of receptacles which is a 30 thing desirable to avoid in tubs designed for toilet purposes. Again in laundry tubs all danger of catching delicate fabrics on depending or outstanding nozzles and tearing them is entirely avoided.

35 It will be understood, of course, that the embodiment of my invention shown and described is merely illustrative, and as such changes as are within the skill of the mechanician, I deem within the purview of my invention, I do not limit myself to anything shown and described except in so far as I am limited by the prior art to which the invention belongs.

I have herein stated that one of the objects of the invention is to provide a construction wherein the delivery passage traverses the face-plate or scutcheon, and has its discharge end directed at right angles to the setting-up nipple, and some of the appended claims have been drawn directly to such an arrangement; but I do not wish to be understood as limiting myself to this specific form of delivery passage, or to a construction wherein the discharge end of the delivery 50 passage is arranged to deliver water at exactly right angles to the setting-up nipple, as it will be obvious that the discharge passage 55 may be otherwise arranged, and so far as some of the claims are concerned the particular direction of the discharge is immaterial.

Having fully described my invention, I claim:

1. A device of the class described comprising a scutcheon or face-plate, an integral setting-up nipple projecting centrally therefrom

on one side, an integrally formed valve chamber projecting centrally therefrom on the opposite side and having its interior walls screw threaded, a valve seat within the chamber integral with the scutcheon or face-plate, an 70 exteriorly threaded valve located within and having its threads in engagement with the threads in the valve chamber, and a delivery passage leading from said chamber at a point coincident with the valve seat and traversing the scutcheon or face plate.

2. A device of the class described comprising a scutcheon or face-plate, an integral setting-up nipple projecting centrally therefrom on one side, an integrally formed valve-casing 80 projecting centrally therefrom on the opposite side and having its interior walls screw-threaded, a valve-seat within the casing formed integral with the scutcheon or face-plate, an exteriorly threaded valve located within and having its threads in engagement with the threads in the valve-casing, and a delivery passage leading from said valve seat and traversing the said face-plate, said delivery passage having its discharge 85 end directed in a line at right angles to the setting-up nipple.

3. A device of the class described, comprising a scutcheon or face-plate 6, an integral setting-up nipple 7, projecting centrally 95 therefrom on one side, an integrally formed valve-casing 8, projecting centrally therefrom on the opposite side and provided with a threaded interior, a valve-seat 12, within the casing formed integral with the scutcheon or face-plate, a valve-stem 14 having a peripherally threaded valve, located within and having its threads in engagement with the threaded interior of the valve-casing, a valve-face 11, on the end of said valve, and a straightway delivery passage 18, leading from 100 said casing and lying close to the said face-plate, said delivery passage having its discharge end directed in a line at right angles to the setting-up nipple.

4. A faucet designed to discharge along a substantially vertical wall of a vessel, comprising a valve-casing provided with a setting-up nipple whereby it may be secured to the vessel wall, an elongated discharge passage opening radially through a wall of the valve-casing, a flange surrounding the base of the casing and traversed by the discharge passage for determining and positioning the said passage close to the vessel wall to secure 115 the stated object, a valve-seat arranged within and formed integral with the casing, a valve, and exposed means for manipulating the valve to control the opening and closing of the discharge passage.

5. A faucet comprising a valve chamber provided at its base with a scutcheon or face-plate and an integrally formed offstanding setting-up nipple whereby it may be secured to a vessel wall, said valve chamber hav-

- a radial discharge passage which traverses a portion of the scutcheon or face plate, a valve-seat formed integral with the scutcheon or face-plate, a valve within the chamber coöperatively associated with the valve-seat and exposed means for manipulating the valve.
6. A faucet comprising a valve-chamber having an abutment at one end provided 10 with a face adapted to abut a wall to which the faucet is to be attached, a setting-up nipple formed integral with said abutment, said valve-chamber having a radial discharge passage which traverses a portion of the abutment, a valve-seat within the valve-chamber at one end thereof, formed integral with the abutment and in line with the discharge passage, a valve coöperatively associated with the valve-seat, and exposed means for manipulating the valve, the construction and arrangement being such that a compact faucet 20 is provided whose discharge passage will be disposed close to the wall to which the faucet is attached.
- 25 7. A faucet comprising a valve chamber provided at its base with a scutcheon or face-plate and an integral setting-up nipple, a valve-seat formed integral with the scutcheon or face-plate, a radial discharge passage 30 leading from the valve seat through a wall of the valve-chamber and traversing said scutcheon or face-plate, a valve coöperatively associated with the valve seat, and exposed means for manipulating the valve.
- 35 8. A faucet comprising an interiorly threaded valve chamber provided with a scutcheon or face-plate and an integral setting-up nipple, a valve-seat formed integral 40 with the scutcheon or face-plate, a discharge passage leading from said seat in a direction at substantially right angles to the setting-up nipple and traversing the scutcheon or face-plate, an exteriorly threaded valve arranged within and having its threads in engagement with the threads of the chamber, and exposed means for manipulating the valve.
- 45 9. A device of the class described comprising a scutcheon or face plate, an integral setting-up nipple projecting centrally therefrom on one side, an integrally formed valve-casing 50 projecting centrally therefrom on the
- other side, a valve seat formed integral with the scutcheon, a valve in said chamber, and a straightway delivery passage leading from 55 said valve chamber and bounded by the said face plate, said delivery passage having its discharge end directed in a line at right angles to the setting-up nipple.
10. A device of the class described comprising a face plate having an integral centrally-disposed setting-up nipple projecting from one side and an integral thickened portion and a valve chamber traversed by a straight through passage, projecting from the 60 opposite side, the surface area of the face-plate being greater than the cross-sectional diameter of the valve-chamber, a valve in said chamber, and a delivery passage at right angles to said through passage traversing 65 said thickened portion of said face-plate, said delivery passage being straight throughout its length.
11. In a device of the class described, a scutcheon or face-plate having formed integral therewith on opposite sides respectively 70 a setting-up nipple and a valve chamber traversed by a straight through passage, a valve in said chamber, and an integral thickened radial section on said face-plate traversed by a straightway passage having its 75 discharge end directed at right angles to and connected with said through passage.
12. A faucet designed to discharge along a substantially vertical wall of a vessel, comprising an interiorly threaded valve-chamber provided with a setting-up nipple whereby it may be secured to the vessel wall, a flange surrounding the base of the chamber, a flattened discharge passage opening radially 80 through a wall of the chamber and traversing said flange, a valve-seat formed integral with the base wall of the chamber, an exteriorly threaded valve arranged within and having its threads in engagement with the threads 85 of the chamber, and exposed means for manipulating the valve.
- In testimony whereof I have hereunto set my hand in presence of two subscribing witnesses.
